[57] CLAIM

The ornamental design for a device for raising and lowering a hanging planter, as shown and described.

DESCRIPTION

FIG. 1 is a side elevational view of the device for raising and lowering a hanging planter showing my new design;

FIG. 2 is a top plan view thereof;

FIG. 3 is a side elevational view taken from the other side thereof;

FIG. 4 is a bottom plan view thereof;

FIG. 5 is a front elevational view thereof;

FIG. 6 is a rear elevational view thereof;

FIG. 7 is a cross-sectional view thereof taken along line 7—7 of FIG. 1;

FIG. 8 is a side elevational view of another embodiment showing my new design;

FIG. 9 is a top plan view thereof;

FIG. 10 is a side elevational view taken from the other side thereof;

FIG. 11 is a bottom plan view thereof;

FIG. 12 is a front elevational view thereof;

FIG. 13 is a rear elevational view thereof; and,

FIG. 14 is a cross-sectional view thereof taken along line 14—14 of FIG. 8.
